UNITED STATES PATENT OFFICE

2,668,050

SPRING GROUP

Robert B. Cottrell, Chicago, and Arthur T. Richardson, Jr., St. Charles, Ill., assignors to American Steel Foundries, Chicago, Ill., a corporation of New Jersey

Application April 12, 1949, Serial No. 87,046

8 Claims. (Cl. 267—9)

1

This invention relates to a package spring group of the type commonly utilized to support a bolster from the side frame of a railway car truck.

A general object of the invention is to devise a package group of the above-described type wherein one of the spaced spring plates of the group comprises a novel friction housing integrally formed with the spring positioning flanges of the plate and having a pair of spaced ledges at each end of the housing adapted to afford wedge surfaces for an associated friction shoe.

A further object of the invention is to provide novel retainer means for limiting expansion of the spring group and retaining the same in precompressed position.

A more specific object of the invention is to devise a package group, such as above described, wherein one of the spring plates is provided with a hollow friction post having an internal web or wall cooperating with retainer means removably mounted on the other plate to limit expansion of the group.

The foregoing and other objects and advantages of the invention will become apparent from a consideration of the following specification and the accompanying drawings, wherein:

Figure 1 is a composite top plan view of a package spring group embodying the invention, the left half of Figure 1 being a top plan view of the group and the right half being a top plan view with the top spring plate and friction shoe removed;

Figure 2 is an end elevational view of the group partly in section on the line 2—2 of Figure 1; and

Figure 3 is a side elevational view.

Describing the invention in detail, the novel package spring group comprises top and bottom spring plates, generally designated 2 and 4, having four spring units, each consisting of an outer coil spring 6 and an inner coil spring 8 compressed between the plates. Each of the plates is provided with cored openings 10 aligned with the coil springs 8 and is provided with a plurality of positioning lugs 12 adapted for reception within complementary openings of the associated supported and supporting members, such as a bolster and side frame (not shown) of a conventional railway car truck. In this connection it may be noted that the group may be inverted with the plate 4 at the top and the plate 2 at the bottom.

The top plate 2 is provided with arcuate end flanges 14 merging with lateral or side flanges 16, said flanges being adapted to afford positioning means for the springs 6 and 8. The top plate 2 also comprises an integral depending friction housing including spaced end walls 18

2

integrally formed with the flanges 16. Each of the end walls is formed with a pair of spaced ledges 20 sloping downwardly and inwardly and adapted to afford wedge seats for an associated friction shoe, as hereinafter described.

The end walls 18 are connected by a pair of side walls 22, the external surfaces of which are reinforced by gussets 24 connected to the underside of the plate 2 at approximately the longitudinal vertical center plane of the group. The lower edges of the side walls 22 are arcuately formed as at 28 and converge inwardly, as best seen in Figure 3, to merge with the lower ends of the ledges 20.

The plate 2 is provided with a pair of V-shaped slots or openings 30 (Figure 2) adapted to receive spaced legs 32 of a retainer strap 34, said legs being welded as at 36 within the openings 30. The strap 34 is reciprocal within a hollow rectangular friction post 38 integrally formed with and upstanding from the bottom plate 4, said post having an internal rib or web 40 within the strap 34 and adapted for engagement therewith, as best seen in Figure 2, to limit the expansion stroke of the group. The post also comprises spaced transverse and longitudinal walls 39 and 43, respectively, and spaced slots 41 in the plane of the rib 40 and adapted for the reception of a key (not shown) adapted to engage the strap to maintain the group under precompression, during assembly of the group, in an associated truck. A pair of friction plates 42, generally parallel to the rib 40, are secured to external surfaces of the post 38 as by welding at 44, the plates being engageable with the associated friction shoes, as hereinafter described.

Each friction plate 42 is engaged by a main or friction wall 52 of a friction shoe, generally designated 54, said shoe having a bottom or spring seat wall 56 and having a pair of spaced ledges 58 each engaged with one of the ledges 20 of the related friction housing wall 18. A spring, diagrammatically indicated at 60, is housed within each shoe for urging the ledges 58 against the engaged ledges 20 and thereby urging the shoe along said ledges into frictional engagement with the related friction plate 42.

The plate 2 and the bottom shoe wall 56 are provided with registrable openings 62 and 64 respectively, adapted for the reception of associated means, such as a bolt and nut assembly for retracting the shoes (not shown) during assembly of the group, as hereinafter described.

The bottom plate 4 comprises end flanges 46 merging with lateral or side flanges 48, each of which is offset as at 50 for the reception of positioning means on an associated supporting side frame member (not shown).

In assembling the novel unit, the springs 60 are inserted into the friction shoes 54 and the latter are seated against the friction housing 2, ledges 20 and are retracted toward the plate 2, as by a bolt and nut assembly extending through the openings 62 and 64 to retain the shoes in their innermost, retracted position within the friction housing. The springs 6 and 8 are then inserted between the plates 2 and 4 which are seated thereagainst and the strap 34 is then inserted into the hollow friction post 38 through an opening 66 in the plate 4 provided for that purpose. The legs 32 of the strap 34 are then entered into the slots 30 of the plate 2 and are welded in the position shown in Figure 2 with the springs 6 and 8 slightly precompressed, if desired. Thereafter, the means are removed from the openings 62 and 64 permitting the shoe actuating springs 60 to urge the shoes into frictional engagement with the plates 42 of the hollow friction post 38, as shown in the drawings.

Thus it will be understood that we have devised a novel package spring group of simple construction and capable of easy assembly. The novel unit also comprises, a removable retainer capable of quick assembly and disassembly and located at the center of the group thereby eliminating the necessary for a plurality of retainers at opposite ends or sides thereof, such as are known in the prior art.

We claim:

1. A package spring group comprising spaced spring plates, a plurality of springs confined therebetween, a friction post carried by one plate, an opening extending through said one plate and through said post from end to end thereof, spaced slots through the other plate, a U-shaped strap insertable through said opening and having spaced legs insertable into respective slots, means securing said legs in said slots, friction means carried by said other plate for frictional engagement with the post, and means connected to the post within said opening and disposed between said legs for engagement with the strap to limit expansion of the group.

2. A spring group, according to claim 1, wherein the post is provided with at least one key slot registrable with the space between the legs of the strap when the group is precompressed.

3. A package spring group comprising spaced spring plates, a plurality of springs confined therebetween, a friction post supported by one plate, an opening extending through said one plate and through said post from end to end thereof, a U-shaped strap insertable through said opening and having spaced legs secured to the other plate, friction means carried by said other plate for developing friction against spaced external surfaces of the post, and a rib in said opening integrally formed with said post and disposed between said legs, said rib being engageable with said strap to limit expansion of the group.

4. A package spring group, according to claim 3, wherein the post is provided with spaced slots disposed in the plane of said rib and adapted for the reception of associated key means insertable through said strap to hold the group in precompression.

5. A package spring group comprising spaced spring plates, a plurality of springs confined therebetween, a friction post carried by one of the plates, an opening through said one plate extending through the post from end to end thereof, said post having an integral rib within said opening at the extremity thereof remote from said one

plate, and a U-shaped retainer receiving said rib and secured to the other plate, and means carried by said other plate for developing friction against said post.

5 6. A package spring group, according to claim 5, wherein the post is provided with spaced aligned slots inwardly of the rib and in alignment therewith for the reception of associated key means adapted to extend through the retainer when the group is precompressed.

10 7. In a spring group having spaced top and bottom plates with coil springs therebetween; the combination of a hollow rectangular friction post connected to said bottom plate centrally of said springs and extending vertically upward from the bottom plate and having an opening extending from end to end and through said bottom plate, said post comprising spaced transverse and longitudinal walls, a pair of spaced friction plates secured on external sides of said longitudinal walls, a horizontally disposed internal rib connected to said transverse walls, wedge means secured to said top plate, a pair of friction shoes in wedge engagement with said wedge means and in frictional engagement with said friction plates, resilient means compressed between the top plate and shoes for urging the shoes into engagement with the friction plates, and a U-shaped strap secured to said top plate and encompassing said rib to prevent disassembly of the spring group and to permit lateral as well as rocking motion of the top plate relative to the bottom plate.

15 8. A spring group of the character described comprising a bottom plate with a spring seat at each corner thereof, a plurality of coil springs positioned in said seats, a hollow rectangular friction post connected to said plate centrally of said springs and extending vertically upward and having an opening extending from end to end and through said plate, said post comprising spaced transverse and longitudinal walls, a pair of spaced friction plates secured on external sides of said longitudinal walls, a pair of aligned and spaced slots in said transverse walls, a horizontally disposed internal rib connected to said transverse walls, a top plate having a spring seat at each corner thereof and being supported by said coil springs, a pair of spaced side walls depending vertically downwardly from said top plate and having aligned wedge shaped ledges at the ends of the walls converging toward the friction plates, a pair of friction shoes each having spaced wedge surfaces in engagement with the respective ledges and a friction surface in engagement with the respective friction wall, spring means compressed between the top plate and shoes for urging the same into engagement with the friction plates, and a U-shaped strap secured at its ends to said top plate and encompassing said rib to accommodate lateral as well as rocking movement of the top plate relative to the bottom plate and to prevent disassembly of the spring group.
